(57) **CLAIM**

The ornamental design for an electronic still camera, as
shown and described.

DESCRIPTION

FIG. 1 is a perspective view of an electronic still camera
showing our new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of a wrist watch strap is shown to
illustrate environment only and forms no part of the claimed
design.
